(57) **ABSTRACT**

A gaming device including a plurality of reels or cards having several symbols. The symbols include at least two complimentary wild symbols that form resultant wild symbols on related reels or cards. In one embodiment, the resultant wild symbol is similar to a wild symbol and acts as a substitute for other symbols on the reels or cards. In another embodiment, the resultant wild symbol transforms adjacent symbols into wild symbols or other symbols on the reels or cards. In a further embodiment, the resultant wild symbol transforms a predetermined or random number of symbols on the reels or cards into wild symbols or other symbols.

GAMING DEVICE HAVING RESULTANT WILD SYMBOLS

PRIORITY CLAIMS

This application claims priority to and the benefits of U.S. Provisional Patent Application Ser. No. 60/376,920, filed Apr. 30, 2002.

CROSS REFERENCE TO RELATED APPLICATIONS

This application relates to the following co-pending commonly owned applications: "GAMING DEVICE HAVING DUAL EVALUATION SCHEME," Ser. No. 09/687,689, "GAMING DEVICE HAVING TRANSFORMABLE WILD SYMBOLS OR CARDS WITH WILD SIGNAL INDICATORS," Ser. No. 09/957,305, "GAMING DEVICE HAVING WILD INDICATORS," Ser. No. 09/960,883, "GAMING DEVICE WITH WILD ACTIVATION SYMBOLS AND WILD TERMINATION SYMBOLS," Ser. No. 09/964,102, "GAMING DEVICE HAVING A VARIED WILD SYMBOL IN A BONUS GAME," Ser. No. 10/243,512, "GAMING DEVICE HAVING SYMBOLS WITH TRANSFORMATION PROBABILITIES," Ser. No. 10/255,880, and "GAMING DEVICE HAVING EXTENDER SYMBOLS," Ser. No. 10/191,197,

BACKGROUND OF THE INVENTION

Gaming devices are well known. Many known gaming devices provide wild symbols or wild cards. Wild symbols provide a player with an additional opportunity to obtain winning combinations. Wild symbols, wild cards and wild indicators in gaming devices also provide additional excitement and entertainment for players.

In a slot machine having reels, a wild symbol can enable the matching of symbols along a payline to achieve a combination. For example, in a three reel slot machine, the symbols along a payline on the first, second and third reels may be, respectively, a heart, a heart and a wild symbol. If, in the gaming scheme, the gaming device awards a player for a three heart combination, the wild symbol substitutes for a heart and provides the player with that combination.

In another example, the gaming scheme is a video poker game. The gaming device displays five cards. The cards are a ten, Jack, Queen, King and wild card. The wild card substitutes as an Ace and provides the player with a winning combination.

Wild cards have been employed in gaming devices in other manners. For example, U.S. Pat. No. 5,431,408 discloses a gaming device having a video poker gaming scheme. A player is dealt a hand consisting of five cards. The player is also given a wild card. The wild card is separate from the dealt hand. The player can reserve the wild card for use with a subsequent hand. Thus, the player can use the wild card in a hand in which it is most advantageous to do so.

In another example, U.S. Pat. No. 6,089,977 discloses a gaming device having a set of virtual reels. The reels display a set of symbols. Certain symbol combinations serve as triggering events. When one of these combinations occur on the reels, a wild card symbol appears on the reels in the form of a graphical image and appears at different locations on the reels. When the wild card symbol appears at each location, the symbol at that location transforms into the wild card symbol. After each activation of the wild symbol, the gaming device determines and pays the player for any

winning combination which is the result of the transformation. When the wild symbol appears at the next symbol, the symbol previously transformed is in its original state.

To increase player enjoyment and excitement, it is desirable to provide gaming devices having new and different wild symbols, wild indicators and wild card schemes.

SUMMARY OF THE INVENTION

The present invention in one embodiment provides a gaming device having resultant wild symbols on a set of reels, on a set of cards or on another set of symbols. The resultant wild symbols are formed from at least two complimentary wild symbols on adjacent or related reels, cards or symbols. The resultant wild symbols act as wild symbols or transform other symbols or cards into wild symbols or wild cards.

In one embodiment of the present invention, the gaming device includes a set of reels having a plurality of symbols displayed within a display device. The plurality of symbols includes at least one resultant wild symbol. The resultant wild symbol includes first and second complimentary wild symbols on adjacent reels. The complimentary wild symbols are positioned on different reels adjacent to one or more symbols on the reels. The complimentary wild symbols are displayed on either side of such symbols. Each complimentary wild symbol is in this embodiment represented by a portion of an image. In one example of this embodiment, the complimentary wild symbols are in the form of left and right halves of a star. In another example of this embodiment, the complimentary wild symbols are in the form of left and right halves of a square. It should be appreciated that any indicia or image could be used to represent the complimentary wild symbols.

In this embodiment, when the complimentary wild symbols are in alignment along a payline of the display device, they combine to create the resultant wild symbol. For example, when a first reel displays a complimentary wild symbol in the form of a left half of a star on the payline, and the adjacent or second reel displays a complimentary wild symbol in the form of a right half of a star on the payline, the processor of the gaming device combines the complimentary wild symbols to create the resultant wild symbol. In this case, the resultant wild symbol is in the form of a complete star. The resultant wild symbol functions as a wild symbol which substitutes for any symbol or a limited group of symbols used in the game to maximize the award.

In one embodiment, when the resultant wild symbol is created within the display device, the processor transforms one or more of the symbols on the reels adjacent to the complimentary wild symbols into a wild symbol. These wild symbols can then substitute for any other symbols or a limited group of symbols used by the gaming device.

In one embodiment, the display device displays a set of cards in a video poker game. At least two cards include a resultant wild symbol. The resultant wild symbol includes a first and second complimentary wild symbol displayed on a first and second card, respectively, which are adjacent or related to each other. In one example, a first card displays a first complimentary wild symbol which is represented by a left half of a square. An adjacent or second card displays a second complimentary wild symbol which is represented by a right half of a square. Because the left half and the right half of the square are complimentary, the processor combines the complimentary wild symbols to create a resultant wild symbol. The resultant wild symbol is played with the rest of the cards, or one or both cards displaying the resultant wild symbol are transformed into wild cards.

In one embodiment, there is a plurality of resultant wild symbols on a set of reels within a display device. In this embodiment, the processor can substitute each resultant wild symbol for symbols or a limited group of symbols used by the gaming device. This can be performed simultaneously, successively or in any combination thereof. In an alternative embodiment, there is a plurality of resultant wild symbols displayed within the display device and the processor transforms symbols adjacent to the resultant wild symbols into wild symbols. The processor transforms the adjacent symbols into wild symbols simultaneously, successively, or in any combination thereof.

In one embodiment, there is a plurality of resultant wild symbols on a set of cards displayed on the display device. The processor transforms those cards displaying the resultant wild symbols into wild cards either simultaneously, successively, or in any combination thereof.

In an alternative embodiment, at least one extender symbol is included on one or more of the reels displayed to a player. The extender symbol extends one or more symbols horizontally, vertically, diagonally or in any other manner across the reels when the extender symbol occurs on one or more reels. The extender symbol may extend a symbol or symbols across a predetermined number of cells or a random number of cells. In one embodiment, the extender symbol acts as a wild symbol. In another embodiment, the extender symbol is included on one or more cards in a set of cards. In this embodiment, the extender symbol extends one or more of the card symbols across at least one card in the set.

It is therefore an advantage of the present invention to provide a gaming device having resultant wild symbols that provide a player with an additional opportunity to obtain a winning combination in a game.

It is another advantage to provide a gaming device having at least one extender symbol that extends symbols and provides a player with an additional opportunity to obtain a winning combination in a game.

Other objects, features and advantages of the invention will be apparent from the following detailed disclosure, taken in conjunction with the accompanying sheets of drawings, wherein like numerals refer to like parts, elements, components, steps and processes.

BRIEF DESCRIPTION OF THE FIGURES

FIGS. 1A and 1B are perspective views of alternative embodiments of the gaming device of the present invention.

FIG. 2 is a schematic block diagram of the electronic configuration of one embodiment of the gaming device of the present invention.

FIG. 3 is a front plan view of a display device displaying a set of reels including a resultant wild symbol.

FIG. 4 is a front plan view of a display device displaying a set of reels in which the resultant wild symbol is transformed into a wild symbol.

FIGS. 5A and 5B are front plan views of a display device displaying a set of reels in which a resultant wild symbol is transformed into a wild symbol.

FIG. 6 is a front plan view of a display device displaying a set of reels including a resultant wild symbol.

FIG. 7 is a front plan view of a display device displaying a set of reels in which the resultant wild symbol transforms symbols on the reels into wild symbols.

FIGS. 8A and 8B are front plan views of a display device displaying a set of reels in which a resultant wild symbol transforms into a wild symbol.

FIG. 9 is a front plan view of a display device displaying a set of reels in which symbols on the reels become wild symbols.

FIG. 10 is a front plan view of a display device displaying a set of cards including a resultant wild symbol.

FIG. 11 is a front plan view of a display device displaying a set of cards in which certain cards become wild cards.

FIG. 12 is a front plan view of a display device displaying a set of cards including a resultant wild symbol.

FIG. 13 is a front plan view of a display device displaying a set of cards in which certain cards become wild cards.

FIG. 14 is a front plan view of a display device displaying a set of reels including a plurality of resultant symbols.

FIG. 15 is a front plan view of a display device displaying a set of reels in which certain symbols become wild.

FIGS. 16A and 16B are front plan views of a display device displaying a set of reels in which certain symbols on the reels become wild.

FIG. 17 is a front plan view of a display device displaying a set of reels including a plurality of resultant wild symbols which become wild.

FIGS. 18A and 18B are front plan views of a display device displaying a set of reels including a plurality of resultant symbols which become wild successively.

FIGS. 19A and 19B are front plan views of a display device displaying a set of cards including a plurality of resultant symbols.

FIGS. 20A and 20B are front plan views of a display device displaying a set of cards including a plurality of resultant symbols which become wild successively.

FIGS. 21A and 21B are front plan views of a display device displaying a set of reels in which a resultant wild symbol transforms the symbol on the right of the resultant wild symbol into the symbol on the left of the resultant wild symbol.

FIGS. 22A and 22B are front plan views of a display device displaying a set of reels in which resultant wild symbols transform the symbols that are adjacent to the resultant wild symbols.

FIGS. 23A and 23B are front plan views of a display device displaying a set of reels in which a resultant wild symbol transforms all of the symbols on the same payline as the resultant wild symbol.

FIGS. 24A and 24B are front plan views of a display device displaying a set of reels in which a resultant wild symbol transforms all of the symbols on the reels that are adjacent to the resultant wild symbol.

FIGS. 25A and 25B are front plan views of a display device displaying a set of reels in which resultant wild symbols transform and upgrade the symbols that are adjacent to the resultant wild symbols.

FIGS. 26A and 26B are front plan views of a display device displaying a set of reels in which an extender symbol horizontally extends a symbol across the reels.

FIG. 26C is a front plan view of a display device displaying a set of reels in which an extender symbol diagonally extends two symbols across the reels.

FIG. 26D is a front plan view of a display device displaying a set of reels in which an extender symbol vertically extends a symbol on a reel.

FIGS. 27A and 27B are front plan views of a display device displaying a set of cards in which an extender symbol horizontally extends two symbols across the cards.

DETAILED DESCRIPTION OF THE INVENTION

Gaming Device and Electronics

Referring now to the drawings, and in particular to FIGS. 1A and 1B, gaming device 10a and gaming device 10b illustrate two possible cabinet styles and display arrangements and are collectively referred to herein as gaming device 10. The present invention includes the game, described below, being a primary game or a bonus or secondary game that coordinates with a base game. When the game of the present invention is a bonus game, gaming device 10 in one base game can be a slot machine having the controls, displays and features of a conventional slot machine, or a video card game such as poker, blackjack, etc. The player can operate the gaming device while standing or sitting. The gaming device may be a pub-style or table-top game (not shown), which a player operates while sitting.

The base games of the gaming device 10 may include slot, poker, or blackjack, among others. The gaming device 10 may also include any bonus triggering events, bonus games as well as any progressive game coordinating with these games. The symbols and indicia used for any of the base, bonus and progressive games include mechanical, electrical, electronic, or video symbols and indicia.

In a stand alone or a bonus embodiment, the gaming device 10 includes monetary input devices. FIGS. 1A and 1B illustrate a coin slot 12 for coins or tokens and/or a payment acceptor 14 for cash money. The payment acceptor 14 may also include other devices for accepting payment, such as readers or validators for credit cards, debit cards or smart cards, tickets, notes, etc. When a player inserts money in gaming device 10, a number of credits corresponding to the amount deposited is shown in a credit display 16. After depositing the appropriate amount of money, a player can begin the game by pulling arm 18 or pushing play button 20. Play button 20 can be any play activator used by the player which starts any game or sequence of events in the gaming device.

As shown in FIGS. 1A and 1B, gaming device 10 also includes a bet display 22 and a bet one button 24. The player places a bet by pushing the bet one button 24. The player can increase the bet by one credit each time the player pushes the bet one button 24. When the player pushes the bet one button 24, the number of credits shown in the credit display 16 decreases by one, and the number of credits shown in the bet display 22 increases by one. A player may "cash out" by pushing a cash out button 26 to receive coins or tokens in the coin payout tray 28 or other forms of payment, such as an amount printed on a ticket or credited to a credit card, debit card or smart card.

Gaming device 10 also includes one or more display devices. The embodiment shown in FIG. 1A includes a central display device 30, and the alternative embodiment shown in FIG. 1B includes a central display device 30 as well as an upper display device 32. The display devices display any visual representation or exhibition, including but not limited to movement of physical objects such as mechanical reels and wheels, dynamic lighting and video images. The display device includes any viewing surface such as glass, a video monitor or screen, a liquid crystal display or any other static or dynamic display mechanism. In a video poker, blackjack or other card gaming machine embodiment, the display device includes displaying one or more cards.

The slot machine base game of gaming device 10 displays a plurality of reels 34, such as three to five reels 34, in

mechanical or video form on one or more of the display devices. Each reel 34 displays a plurality of indicia such as bells, hearts, fruits, numbers, letters, bars or other images which preferably correspond to a theme associated with the gaming device 10. If the reels 34 are in video form, the display device displaying the video reels 34 is preferably a video monitor. Each base game, especially in the slot machine base game of the gaming device 10, includes speakers 36 for making sounds or playing music.

Referring now to FIG. 2, a general electronic configuration of the gaming device 10 for the stand alone and bonus embodiments described above preferably includes: a processor 38; a memory device 40 for storing program code or other data; a central display device 30; an upper display device 32; a sound card 42; a plurality of speakers 36; and one or more input devices 44. The processor 38 is preferably a microprocessor or microcontroller-based platform which is capable of displaying images, symbols and other indicia such as images of people, characters, places, things and faces of cards. The memory device 40 includes random access memory (RAM) 46 for storing event data or other data generated or used during a particular game. The memory device 40 also includes read only memory (ROM) 48 for storing program code, which controls the gaming device 10 so that it plays a particular game in accordance with applicable game rules and pay tables.

As illustrated in FIG. 2, the player preferably uses the input devices 44 to input signals into gaming device 10. In the slot machine base game, the input devices 44 include the pull arm 18, play button 20, the bet one button 24 and the cash out button 26. In certain instances, it is preferable to use a touch screen 50 and an associated touch screen controller 52 instead of a conventional video monitor display device. The touch screen enables a player to input decisions into the gaming device 10 by sending a discrete signal based on the area of the touch screen 50 that the player touches or presses. A touch screen 50 and touch screen controller 52 are connected to a video controller 54 and processor 38. The terms "computer" or "controller" are used herein to refer collectively to the processor 38, the memory device 40, the sound card 42, the touch screen controller and the video controller 54. As further seen in FIG. 2, the processor 38 connects to the coin slot 12 or payment acceptor 14, whereby the processor 38 requires a player to deposit a certain amount of money in to start the game.

It should be appreciated that although a processor 38 and memory device 40 are preferable implementations of the present invention, the present invention also includes being implemented via one or more application-specific integrated circuits (ASIC's), one or more hard-wired devices, or one or more mechanical devices (collectively or alternatively referred to herein as a "processor"). Furthermore, although the processor 38 and memory device 40 preferably reside in each gaming device 10 unit, the present invention includes providing some or all of their functions at a central location such as a network server for communication to a playing station such as over a local area network (LAN), wide area network (WAN), Internet connection, microwave link, and the like.

With reference to the slot machine base game of FIGS. 1A and 1B, to operate the gaming device 10, the player inserts the appropriate amount of tokens or money in the coin slot 12 or the payment acceptor 14 and then pulls the arm 18 or pushes the play button 20. The reels 34 then begin to spin. Eventually, the reels 34 come to a stop. As long as the player has credits remaining, the player can spin the reels 34 again. Depending upon where the reels 34 stop, the player may or may not win additional credits.

Resultant Wild Symbols

In one embodiment of the present invention, the display device 30 displays three reels 34a, 34b and 34c, as illustrated in FIG. 3. The reels contain a set of symbols 60 such as hearts, cherries, numbers, or any other suitable symbols. The reels include at least one resultant wild symbol 62. The resultant wild symbol 62 includes at least two complimentary wild symbols 64a and 64b on adjacent or related reels 34a and 34b. The complimentary wild symbols are, for example, represented by portions of an image. In one embodiment, each complimentary wild symbol is in the form of a portion of a word, design, picture, or the like. In one embodiment, each complimentary wild symbol is in the form of a portion of a symbol used by the gaming device. Preferably, the complimentary wild symbols are displayed on either side of the symbols. It should be appreciated that the resultant wild symbol may be associated with one or more awards including but not limited to multipliers, free games and free spins.

In the illustrated embodiment of FIG. 3, a player uses the control features of the gaming device to cause the reels to spin. When the reels stop spinning, the first reel 34a includes the "7" symbol 60a and a complimentary wild symbol 64a in the form of a left half of a star along a payline 56, as illustrated in FIG. 3. The second reel 34b includes a complimentary wild symbol 64b in the form of a right half of a star and the "7" symbol 60b. The third reel includes the "BAR" symbol 60c. The processor combines the complimentary wild symbols 64a and 64b to create the resultant wild symbol 62. The resultant wild symbol 62 functions as a wild symbol that combines with the adjacent symbols 60a and 60b to form a winning combination of three "7's, as illustrated in FIG. 4. The processor awards the player for the winning by displaying the player's new credit total in the credit display 16.

In one embodiment, the gaming device provides a signal to the player that the complimentary wild symbols 64a and 64b have combined to create a resultant wild symbol 62. In this embodiment, the signal is the displaying of the word "WILD" through symbols 65a and 65b. The signal may also be a sound or message emitted by a speaker. Other suitable audio or visual methods of notifying a player are contemplated by the present invention.

In another example, a first reel 34a includes a "BAR" symbol 60d and a complimentary wild symbol 64c in the form of a left half of a star along a payline 57, as illustrated in FIG. 5A. The first reel also includes the "7" symbol and a complimentary wild symbol 64a in the form of a left half of a star. The second reel includes a complimentary wild symbol 67a in the form of a right half of a square and a "BAR" symbol 60e in the upper portion of the display device. The second reel also includes a complimentary wild symbol 64b in the form of a right half of a star and a cherry symbol 60b. No resultant wild symbol is created with respect to symbols 64c and 67a. However, the processor combines the complimentary wild symbols 64a and 64b to create a resultant wild symbol 62, as illustrated in FIG. 5B. According to the payable of the gaming device, the player is not awarded any credits for obtaining two "7's, two cherry symbols or two "BAR" symbols. If the third reel had included a cherry symbol along payline 56, the player would have been awarded for having three cherries. This embodiment illustrates multiple resultant wild symbols, as well as multiple complimentary wild symbols which are the same on one reel and are both adapted to match a single complimentary wild symbol on another reel.

In one embodiment, the processor transforms one or more symbols adjacent to resultant wild symbol into wild symbols. For example, within the display device, a first reel includes the "7" symbol 60a and a complimentary wild symbol 64a in the form of a left half of a star along payline 56, as illustrated in FIG. 6. The second reel 34b includes a complimentary wild symbol 64b in the form of a right half of a star along payline 56 as well as the "7" symbol 60b. The third reel includes a "BAR" symbol 60c. The processor 5 combines the complimentary wild symbols to create a resultant wild symbol 62. As a result, the "7" symbol 60a displayed on the first reel and the "7" symbol 60b on the second reel become wild symbols 69a and 69b as illustrated in FIG. 7. The wild symbols combine with the BAR symbol 10 on the third reel to provide three "BAR" symbols along the payline 56.

In one embodiment, the processor creates a resultant wild symbol by combining complimentary wild symbols on non-adjacent reels. For example, in a gaming device having three 15 reels, complimentary wild symbols 64a and 64b are present along a payline 56 on the first and third reels, respectively, as illustrated in FIG. 8A. The first reel includes a complimentary wild symbol 64b in the form of a right half of a star and a "BAR" symbol 60d. The third reel includes a "BAR" symbol 60e and a complimentary wild symbol 64a in the form of a left half of a star. The complimentary wild symbols 64b and 64a on the first and third reels, respectively, are combined by the processor to create a resultant wild symbol. The processor then combines the "BAR" symbol 60d on the first reel with the resultant wild symbol and the "BAR" symbol 60e on the third reel to produce three "BAR" symbols as illustrated in FIG. 8B. The processor awards the player for the winning combination. It should be appreciated that this type of combination of complimentary wild symbols is not limited to embodiments having three reels, and can include any number of reels where complimentary wild symbols are present on two related or adjacent reels.

In an alternative embodiment, the symbols adjacent to the resultant symbol become wild symbols as a result of the complimentary wild symbol combination. The "BAR" symbols 60d and 60e on the payline 56 of the first and third reels become wild symbols 69a and 69c, respectively, as illustrated in FIG. 9. The second reel 34b includes a heart symbol 60a; as a result, the wild symbols each substitute for a heart symbol. The player obtains three heart symbols and is provided any associated award.

In a further embodiment, the gaming device provides the player with a plurality of spins at the beginning of the game. The player or the processor spins the reels until there are no 45 spins remaining in the game.

In still a further embodiment, a probability of occurring on the reels is associated with each resultant wild symbol such that the probability of one resultant wild symbol occurring on the reels is greater than the probability of two or more resultant wild symbols occurring on the reels.

In one alternative embodiment, the resultant wild symbols are displayed within a display device on a set of cards such as in a video poker game. The resultant wild symbols include complimentary wild symbols displayed on separate cards. For example, a player uses the control features of the gaming device to have the processor deal a set of cards 70a through 60 70e, as illustrated in FIG. 10. The first card 70a includes a complimentary wild symbol 72a in the form of a left half of a star. The second card 70b includes a complimentary wild symbol 72b in the form of a right half of a star. The processor 65 combines the complimentary wild symbols to create a

resultant wild symbol **74**. For one embodiment, the processor transforms the first and second cards into wild cards **80a** and **80b**, respectively, as illustrated in FIG. 11. These cards substitute for any other cards used in the game. In another embodiment, the processor transforms one of such cards into a wild symbol. In another embodiment, the processor sequentially transforms each card into wild symbol and makes a determination of any winning hand after each transformation. In another embodiment, the resultant wild symbol is an extra wild symbol used with the other displayed cards.

In another embodiment, a resultant wild symbol is formed from the combination of complimentary wild symbols on related but non-adjacent cards. In one example, five cards **70a** through **70e** are displayed within a display device as illustrated in FIG. 12. The first and fifth cards have complimentary wild symbols **72b** and **72a**, respectively. The processor combines the complimentary wild symbols to create a resultant wild symbol. In one embodiment, the processor transforms the first and fifth cards **70a** and **70e** into wild cards **80a** and **80e**, respectively, as illustrated in FIG. 13. It is appreciated that this type of combination of complimentary wild symbols is not limited to embodiments having five cards and can include any plurality of cards. It should also be appreciated that alternative suitable wild card transformations as described above may be performed by the processor.

The resultant wild symbols can function as wild symbols either simultaneously or successively. In one example, a display device displays four reels, as illustrated in FIG. 14. The first reel **34a** includes along payline **56** a complimentary wild symbol **64b** in the form of a right half of a star, a "7" symbol **60a** and another complimentary symbol **64a** in the form of a left half of a star. The second reel **34b** includes along payline **56** a complimentary wild symbol **64b** in the form of a right half of a star, a heart symbol **60b** and a complimentary symbol **64c** in the form of a left half of a square. The third reel **34c** includes along payline **56** a complimentary wild symbol **64d** in the form of a right half of a square, the "7" symbol **60c** and another complimentary wild symbol **64a** in the form of a left half of a star. The fourth reel **34d** includes along payline **56** complimentary wild symbol **64d** in the form of a right half of a square, a "BAR" symbol **60d**, and a complimentary wild symbol **64c** in the form of a left half of a square.

In this example, the processor combines complimentary wild symbols **64a** and **64b** to create resultant wild symbol **62a**. In addition, the processor combines complimentary wild symbols **64c** and **64d** to create resultant wild symbol **62b**. If the processor transforms the symbols along the payline **56** adjacent to the resultant wild symbols into wild symbols **69a**, **69b** and **69c** simultaneously, as illustrated in FIG. 15, the player receives four "BAR" symbols.

However, if the processor transforms the symbols adjacent to the resultant wild symbols into wild symbols successively, as illustrated in FIGS. 16A and 16B, then the player obtains a first combination of three "7" symbols or three "BAR" symbols. Next, the second resultant wild symbol causes the adjacent symbols to become wild. The player receives three "7" symbols or three "BAR" symbols a second time.

If the processor transforms the resultant wild symbols **62a** and **62b** into wild symbols, the player obtains four "7" symbols, as illustrated in FIG. 17. If the processor transforms the resultant wild symbols **62a** and **62b** into wild symbols successively, as illustrated in FIGS. 18A and 18B,

the player first receives a combination of three "7" symbols. Next, the processor combines complimentary wild symbols **64c** and **64d** to create a resultant wild symbol **62b**. The player again obtains three "7" symbols.

In one alternative embodiment, a plurality of resultant wild symbols **74a** and **74b** are included on a set of five cards **70a** through **70e** displayed in a video poker game, as shown in FIG. 19A. The resultant wild symbols are included on the first and second cards **70a** and **70b** as well as the fourth and fifth cards **70d** and **70e**. The processor transforms the cards into wild cards simultaneously, successively, or in any combination thereof.

If the cards including the resultant wild symbols are transformed into wild cards **80a**, **80b**, **80d** and **80e** simultaneously, as illustrated in FIG. 19B, the player receives five Queens. If the cards including the resultant wild symbols are transformed successively, the first and second cards **70a** and **70b** are transformed into wild cards **80a** and **80b**, respectively, as illustrated in FIG. 20A. The player receives three Aces. Next, the fourth and fifth cards **70d** and **70e** are transformed into wild cards **80d** and **80e**, as illustrated in FIG. 20B. The player then receives a straight.

Other alternative embodiments are illustrated in FIGS. 21 to 25. In these embodiments, the resultant wild symbol **62** extends or transforms one or more symbols on the reels, either horizontally, vertically and in any combination desired by the game implementor.

Referring now specifically to FIG. 21a, a resultant wild symbol **62** is formed from a complimentary wild symbol **64a** which is in the form of a left side of a star and complimentary symbol **64b** which is in the form of a right side of a star. In one embodiment, the resultant wild symbol **62** extends one or more symbols horizontally across the reels. The resultant wild symbol may extend a symbol across any number of reels such as one reel, two reels or all of the reels. As illustrated in FIG. 21b, the resultant wild symbol **62** extends the "7" symbol **60a** to the second reel **34b**. The resultant wild symbol **62** may extend a symbol and/or it may act as a substitute or wild symbol. In FIG. 21b, the resultant wild symbol **62** performs both functions by acting like a wild symbol and forms a three "7" symbols on payline **56**. It should be appreciated that the resultant wild symbol **62** may extend a symbol that is adjacent to it, diagonal to it, or in any other related position or randomly picked position on the reels as desired by the game implementor. It should also be appreciated that the resultant wild symbol **62** may extend a symbol across one or more reels **34** (i.e., skipping or not skipping certain symbols or symbol positions). A resultant wild symbol can also extend a symbol across a predetermined number of reels or a random number of reels. Accordingly, it should be appreciated that the resultant wild symbol can also function as an extender symbol.

Referring now to FIGS. 22a and 22b, two resultant wild symbols **62a** and **62b** are formed on the reels by complimentary symbols **64a** and **64b**, and **64c** and **64d**, respectively. A first resultant wild symbol **62a** is formed from a left side of a star **64a** and a right side of a star **64b**. The resultant wild symbol **62b** is formed from a left side of a star **64c** and a right side of star **64d**. In this alternative embodiment, the "7" symbol **60a** on the left side of the resultant wild symbol **62a** is extended across the reels to those reels that are adjacent to a resultant wild symbol **62a** and **62b**. As illustrated in FIG. 22b, the "7" symbol **60a** is extended across reels **34a**, **34b**, **34c** and **34d**. Note that the cherry symbol **60e** is not transformed into a "7" symbol because the cherry symbol **60a** was not adjacent to one of the resultant wild

symbols **62a** or **62b**. The final symbol combination is four “7” symbols **60a**, **60b**, **60c** and **60d** in a row. In another embodiment, the resultant wild symbols **62a** and **62b** also functions like a wild symbol and are substituted for the symbol that is extended across the reels. In this case, the symbol combination includes six “7” symbols aligned across the reels.

In another alternative embodiment illustrated in FIGS. 23a and 23b, the resultant wild symbol **62** extends a symbol across a predetermined number of reels. In this embodiment, the resultant wild symbol **62** is formed from the left side of a star **64a** and from the right side of a star **64b**. A resultant wild symbol extends the symbol to the left of the resultant wild symbol **62**, which is the “7” symbol **60a**, across a predetermined number of reels. In this case, the resultant wild symbol **62** extends the “7” symbol **60a** across all of the reels **34**. As shown in FIG. 23b, the “7” symbol **60a** is extended across or to reels **34b**, **34c**, **34d** and **34e**. The final symbol combination becomes five “7” symbols on the payline **56**. In another embodiment, the resultant wild symbol **62** acts like a wild symbol and is substituted with the “7” symbol **60a**. Thus, the final symbol combination is six “7” symbols across payline **56**. It should be appreciated that the resultant wild symbol **62** may extend a symbol across a predetermined or random number of reels.

Referring now to FIGS. 24a and 24b, the resultant wild symbol **62** extends the symbols that are vertically adjacent to the resultant wild symbol on the reels. In this example, there are five reels **34a** to **34e** and a resultant wild symbol **62** is formed from a two complimentary wild symbols **64a** and **64b**. The resultant wild symbol **62** is a star which is formed from a left side of a star **64a** on reel **34a** and from a right side of a star **64b** on reel **34b**. As illustrated in FIG. 24b, the resultant wild symbol **62** extends the adjacent “7” symbol **60a** to the adjacent reel **34b** and thereby transforms the heart symbol **60b** shown in FIG. 24a to a “7” symbol **60b** in FIG. 24b. Then, the “7” symbol **60a** and **60b** are extended vertically on reels **34a** and **34b**. The “BAR” symbols **60f** and **60g** and the cherry symbol **60h** are transformed into the “7” symbol. As shown in FIG. 24b, all of the symbols on reels **34a** and **34b** have been transformed into “7” symbols as a result of the resultant wild symbol **62**.

In this example, the resultant combination on payline **56** does not provide a winning combination of three or more symbols unless the resultant wild symbol **62** acts like a wild symbol. If the resultant wild symbol acts as a wild symbol, the resultant wild symbol **62** forms the combination of three “7” symbols on the payline **56**. In another embodiment, the processor employs a scatter pay combination where any three symbols across the paylines provides a winning combination. Therefore, any of the three “7” symbols on reels **34a** and **34b** provides a winning combination. It should be appreciated that vertically extending one or more symbols on the reels may create a winning combination of symbols or may eliminate a winning combination of symbols, depending on which symbol or symbols are being extended on the reels.

In an alternative embodiment, the extender symbol only extends a symbol on the reels to improve the award or payout to the player in a particular activation of the reels. If an award is eliminated, decreased or remains the same based on the extension of a symbol on the reels by the extender symbol, the symbol is not extended on the reels. For example in a particular game, the extender symbol extends a symbol across one reel and also acts as a wild symbol. In addition, three “BAR” symbols provide a larger award to the player than three cherry symbols in the game. The player

activates the reels and obtains a cherry symbol, an extender symbol, and three “BAR” symbols on a payline associated with the reels. If the cherry symbol is extended by the extender symbol, there will be three cherry symbols instead of three “BAR” symbols indicated on the payline, which decreases the award in that activation. Therefore, the extender symbol does not extend the cherry symbol across the reels because extending the cherry symbol decreases the award provided to the player.

Referring now to FIGS. 25a and 25b, another alternative embodiment is shown where the resultant wild symbols **62a** and **62b** are adjacent to each other on payline **56**. In this embodiment, when one or more resultant wild symbols **62** are formed by two complimentary wild symbols and are adjacent to each other on the reels **34**, the symbols adjacent to the resultant wild symbol **62** are upgraded to the highest symbol on the reels. In this example, the highest or most valuable symbol is the “BAR” symbol **60d**. Therefore, the symbols adjacent to the resultant wild symbols **62a** and **62b**, which in this case are symbols **60a**, **60b** and **60c**, are upgraded to the “BAR” symbol. The resultant winning combination on payline **56** is four “BAR” symbols or six “BAR” symbols if the resultant wild symbols **62a** and **62b** act as wild symbols. The adjacent resultant wild symbols **62a** and **62b** may also provide one or more multipliers to the player, which multiplies the award for the winning combination by a predetermined or random amount or value. Also, the adjacent resultant wild symbols may extend the symbols across the reels horizontally or vertically or perform any other function desired by the game implementor. It should also be appreciated that the resultant wild symbol **62** in this alternative embodiment may act as a wild symbol and thereby substitute for or transform into a symbol on the reels or simply extend one or more symbols on the reels.

Referring to FIGS. 26A, 26B, 26C and 26D, in a further alternative embodiment of the present invention, the gaming device includes at least one extender symbol on the reels. In one embodiment, the extender symbol horizontally extends one of the symbols, which is adjacent to the extender symbol on the reels, to one or more other reels. It should be appreciated that the extender symbol may extend one or more symbols across the reels. It should also be appreciated that the extender symbol may extend a symbol horizontally, vertically, diagonally or in any manner desired by the game implementor.

Referring to FIG. 26A, the gaming device displays five reels to the player having one payline **56**. The player spins the reels. After the reels stop spinning, a “BAR” symbol **60a**, an extender symbol **80**, a cherry symbol **60b**, a cherry symbol **60c** and a heart symbol **60d** occur on payline **56**. In this example, the extender symbol **80** horizontally extends the bar symbol **60a** from reel **34a** to reel **34c**. This transforms the cherry symbol **60b** to a “BAR” symbol **60b** as illustrated in FIG. 26B. In one embodiment, the extender symbol does not act as a wild symbol and therefore, there are only two “BAR” symbols **60a** and **60b** on payline **56**. In another embodiment, the extender symbol acts as a wild symbol and as a result, there are three “BAR” symbols on payline **56**. The player receives the award or awards associated with the resultant combination of symbols on the reels.

Referring to FIG. 26C, another aspect of this embodiment is illustrated where the extender symbol **80** extends the adjacent symbols, bar symbol **60e** and complimentary wild symbol **64a** (which is in the form of the left side of a star), diagonally across the reels from reel **34a** to reel **34c**. As a result, the heart symbol at the bottom of the reel **34c** (shown

13

in FIG. 26B) transforms into the “BAR” symbol **60e** and the complimentary wild symbol **64a**. The extended complimentary wild symbol **64a** combines with the complimentary wild symbol **64b** (which is in the form of the right side of a star) on reel **34d** to form resultant wild symbol **62a**. As a result, three “BAR” symbols occur on the bottom payline **58**. Therefore, the extender symbol can create additional winning combinations on the reels which adds excitement and enjoyment to the player.

Referring to FIG. 26D, a further aspect of this embodiment is illustrated where the extender symbol **80** vertically extends bar symbol **60e** on reel **34b** from the top to the bottom of reel **34b**. As a result, there are two bar symbols on reel **34b**. It should be appreciated that the extender symbol may extend one or more symbols on the reels. Additionally, the extender symbol can extend a symbol across a predetermined number of reels or a random number of reels.

Referring to FIGS. 27A and 27B, a further alternative embodiment of the present invention is illustrated where the extender symbol is included on one or more playing cards. The gaming device displays or deals five playing cards to a player as shown in FIG. 27A. In this example, the cards **70a**, **70b**, **70c**, **70d** and **70e** include the King of diamonds, Queen of hearts, Ace of clubs, two of clubs and three of diamonds, respectively. The extender symbol **80** appears on card **70b** and extends one or more of the symbols on the cards. In one embodiment, the extender symbol extends one of the adjacent card symbols across the cards such as the King symbol. In another embodiment, the extender extends both symbols across the cards such as the King symbol and the suit symbol (i.e., hearts, clubs). Moreover, the extender may extend a symbol across one or more cards as desired. In another embodiment, the extender symbols acts as a wild symbol as described above.

Referring to FIG. 27B, the extender symbol **80** extends both symbols of card **70a**, the King symbol and the diamond symbol, across card **70b** to card **70c**. Now card **70c** is also a King of diamonds. In this example, the extender symbol does not act as a wild symbol. Therefore, the player obtains two pair (i.e., two king of diamond cards) resulting as a result from the extension function performed by the extender symbol **80**.

While the present invention is described in connection with what is presently considered to be the most practical and preferred embodiments it should be appreciated that the invention is not limited to the disclosed embodiments, and is intended to cover various modifications and equivalent arrangements included within the spirit and scope of the claims. Modifications and variations in the present invention may be made without departing from the novel aspects of the invention as defined in the claims, and this application is limited only by the scope of the claims.

The invention is claimed as follows:

1. A gaming device comprising:

a plurality of reels including at least two adjacent reels; a processor which controls the reels; a plurality of symbols on the reels; at least two complimentary wild symbols included in the plurality of symbols, each said complimentary wild symbol on a different one of said adjacent reels; and a resultant wild symbol formed by said two complimentary wild symbols when said complimentary wild symbols both occur on said adjacent reels, wherein the processor transforms at least one symbol which occurs on the reels to one of the other symbols when the resultant wild symbol is formed on said adjacent reels.

14

2. The gaming device of claim 1, which includes a payline associated with the reels, wherein the processor transforms at least one symbol which occurs on the reels to one of the other symbols when the resultant wild symbol is formed on the payline.

3. The gaming device of claim 1, which includes a payline associated with the reels, wherein the processor transforms at least one symbol which occurs on the payline when the resultant wild symbol is formed on the payline.

10 4. The gaming device of claim 1, which includes a plurality of resultant wild symbols and a plurality of sets of two complimentary wild symbols on the reels, wherein each set of two complimentary wild symbols forms one of the resultant wild symbols.

15 5. The gaming device of claim 4, which includes a probability of each of the resultant wild symbol forming on the reels, wherein the probability of one of the resultant wild symbols forming on the reels is greater than the probability of another of the resultant wild symbols forming on the reels.

20 6. The gaming device of claim 1, which includes an award provided to a player if the resultant wild symbol causes a winning combination of symbols to occur on the reels.

25 7. The gaming device of claim 1, wherein the resultant wild symbol transforms into one of the symbols that is adjacent to the resultant wild symbol on the reels, resulting in at least three symbols on the adjacent reels.

8. The gaming device of claim 1, wherein the resultant wild symbol functions as a wild symbol.

30 9. The gaming device of claim 1, wherein the resultant wild symbol functions as an extender symbol which extends one or more symbols across the reels.

35 10. The gaming device of claim 1, wherein the symbols include at least one extender symbol which extends one or more symbols across the reels.

11. The gaming device of claim 10, wherein the extender symbol functions as a wild symbol.

12. The gaming device of claim 1, wherein the symbols include at least one extender symbol which extends one or 40 more symbols across a predetermined number of reels.

13. The gaming device of claim 1, wherein the symbols include at least one extender symbol which extends one or more symbols across a random number of reels.

45 14. The gaming device of claim 1, wherein the symbols include at least one extender symbol which extends a plurality of the symbols across a predetermined number of reels.

50 15. The gaming device of claim 1, wherein the symbols include at least one extender symbol which extends a plurality of the symbols across a random number of reels.

16. The gaming device of claim 1, which includes at least two different sets of complimentary symbols on the reels, wherein each set forms a different resultant wild symbol.

55 17. A gaming device comprising:
a plurality of reels;
a processor which controls the reels;
a plurality of symbols on the reels;
at least two complimentary wild symbols included in the plurality of symbols; and
a resultant wild symbol formed by said two complimentary wild symbols when said complimentary wild symbols both occur on related reels, wherein the processor causes the resultant wild symbol formed on the reels to function as an extra symbol which occurs on the reels.

60 65 18. The gaming device of claim 17, which includes a payline associated with the reels, wherein when the resultant

15

wild symbol is formed on the payline, the processor causes the resultant wild symbol to function as an extra symbol on said payline.

19. The gaming device of claim 17, which includes a payline associated with the reels, wherein the processor transforms at least one symbol on the payline associated with the reels to another of the symbols when the resultant wild symbol is formed on the payline. 5

20. A gaming device comprising:

a plurality of reels including at least two adjacent reels; a processor which controls with the reels; a plurality of symbols on the reels;

at least two complimentary wild symbols included in the plurality of symbols, each said complimentary wild symbol on a different one of the adjacent reels; and a resultant wild symbol formed by said two complimentary wild symbols when said complimentary wild symbols both occur on said adjacent reels, wherein the processor causes at least one symbol which occurs on the reels to function as another one of said plurality of symbols when the resultant wild symbol is formed on the reels. 15

21. A gaming device comprising:

a plurality of reels including at least two adjacent reels; a processor which controls with the reels; a plurality of symbols on the reels;

a payline associated with the reels; at least two complimentary wild symbols included in the plurality of symbols, each said complimentary wild symbol on a different one of the adjacent reels; and a resultant wild symbol formed by said two complimentary wild symbols when the two complimentary wild symbols both occur on the adjacent reels on the payline, wherein the processor transforms at least one symbol which occurs on the payline to one of the plurality of symbols when the resultant wild symbol is formed on the payline. 20

22. The gaming device of claim 21, wherein the processor transforms at least one symbol adjacent to the resultant wild symbol on a payline to one of the plurality of symbols when the resultant wild symbol is formed on the payline.

23. The gaming device of claim 21, wherein the resultant wild symbol transforms into one of the symbols on the payline adjacent to the resultant wild symbol when the resultant wild symbol is formed on the payline. 25

24. A gaming device comprising:

a plurality of reels; a processor which controls with the reels; a plurality of symbols on the reels;

a plurality of sets of complimentary wild symbols included in the plurality of symbols; and a plurality of resultant wild symbols, wherein each resultant wild symbol is formed by one of the sets of complimentary wild symbols when said set of complimentary wild symbols occurs on related reels and wherein the processor transforms at least one symbol which occurs on the reels to one of the plurality of symbols when one or more resultant wild symbols are formed on the reels. 30

25. The gaming device of claim 24, wherein each set of complimentary wild symbols are arranged on the reels such that each set can simultaneously form one of the resultant wild symbols. 35

16

26. A gaming device comprising: a plurality of reels; a processor which occurs with the reels; a plurality of symbols on the reels; a plurality of sets of complimentary wild symbols included in the plurality of symbols; and a plurality of resultant wild symbols, wherein each resultant wild symbol is formed by said one of the sets of complimentary wild symbols when said set of complimentary wild symbols occurs on related reels and wherein the processor causes at least one symbol which occurs on the reels to function as another one of said plurality of symbols when each resultant wild symbol is formed on the reels. 40

27. The gaming device of claim 26, which includes at least one payline, wherein one of the resultant wild symbols is formed when one set of complimentary wild symbols occurs on the payline on adjacent reels.

28. The gaming device of claim 26, wherein each resultant wild symbol is transformed into one of the symbols adjacent to said resultant wild symbol.

29. A method of operating a gaming device, said method comprising the steps of:

(a) displaying a plurality of reels having a plurality of symbols, said symbols including at least two complimentary wild symbols on adjacent reels;

(b) activating said reels;

(c) forming a resultant wild symbol when said two complimentary wild symbols both occur on the adjacent reels; and

(d) transforming at least one symbol which occurs on the reels to one of the plurality of symbols when the resultant wild symbol is formed on the adjacent reels. 45

30. The method of claim 29, which includes a plurality of sets of two complimentary wild symbols on adjacent reels and the step of forming a plurality of resultant wild symbols on the reels, wherein each resultant wild symbol is formed by one of said sets of complimentary wild symbols.

31. The gaming device of claim 29, which includes providing an award to a player if the resultant wild symbol causes a winning combination of the symbols to occur on the reels.

32. The method of claim 31, wherein the award is selected from the group consisting of: at least one credit, a multiple of a player's wager and at least one free spin of the reels.

33. The method of claim 29, which includes the step of providing an award to the player after the resultant wild symbol is formed on the reels.

34. The method of claim 29, which includes a plurality of resultant wild symbols on the reels and which includes the step of providing an award to the player after the resultant wild symbols are formed on the reels. 50

35. The gaming device of claim 29, which includes the step of extending one of the symbols which occurs on the reels across a predetermined number of the reels when at least one extender symbol occurs on the reels.

36. The gaming device of claim 29, which includes the step of extending one of the symbols which occurs on the reels across a random number of the reels when at least one extender symbol occurs on the reels. 55

37. The gaming device of claim 29, which includes the step of extending one of the symbols which occurs on the reels vertically on one or more of the reels when at least one extender symbol occurs on the reels.

38. The gaming device of claim 29, which includes the step of extending a plurality of the symbols which occur on

the reels across a predetermined number of the reels when at least one extender symbol occurs on the reels.

39. The gaming device of claim **29**, which includes the step of extending a plurality of the symbols which occur on the reels across a random number of the reels when at least one extender symbol occurs on the reels.

40. The method of claim **29**, wherein the method is provided to a player through a data network.

41. The method of claim **40**, wherein data network is an internet.

42. A method of operating a gaming device, said method comprising the steps of:

- (e) displaying a plurality of reels having a plurality of symbols, said symbols including at least two complimentary wild symbols on adjacent reels;
- (f) activating said reels;
- (g) forming a resultant wild symbol when said two complimentary wild symbols occur on the adjacent reels; and
- (h) causing the resultant wild symbol formed on the adjacent reels to function as an extra symbol on the adjacent reels.

43. The method of claim **42**, which includes the step of transforming at least one symbol which occurs on a payline associated with the reels to one of the plurality of symbols when the resultant wild symbol is formed on the payline.

44. The method of claim **42**, wherein the method is provided to a player through a data network.

45. The method of claim **44**, wherein data network is an internet.

46. A gaming device comprising:

- a processor;
- a display device controlled by the processor;
- a plurality of cards adapted to be randomly selected by the processor and displayed by the display device;
- a plurality of symbols included on the cards;
- at least two complimentary wild symbols included in the plurality of symbols; and
- a resultant wild symbol formed by said two complimentary wild symbols on related cards, wherein the processor transforms at least one symbol which occurs on the card to one of the plurality of symbols when the resultant wild symbol is formed on the cards.

47. The gaming device of claim **46**, wherein the related cards are adjacent cards.

48. The gaming device of claim **46**, wherein the related cards are non-adjacent cards.

49. The gaming device of claim **46**, which includes a plurality of sets of two complimentary wild symbols and a plurality of resultant wild symbols on the cards, wherein each of the resultant wild symbols are formed by one of the sets of said complimentary wild symbols.

50. The gaming device of claim **49**, which includes a probability of each of the resultant wild symbols forming on the cards, wherein the probability of one of the resultant wild symbols forming on the cards is greater than the probability of one of the other resultant wild symbol forming on the cards.

51. The gaming device of claim **49**, which includes an award provided to a player if at least one of the plurality of resultant wild symbols causes a winning combination of symbols on the cards.

52. The gaming device of claim **51**, wherein the award provided to the player is selected from the group consisting of: at least one credit, a multiple of a player's wager and at least one free play of the cards.

53. The gaming device of claim **46**, which includes an award provided to a player after a resultant wild symbol is formed on the cards.

54. The gaming device of claim **46**, wherein the resultant wild symbol functions as an extender symbol which extends one or more of the symbols which occur on the cards across the cards.

55. The gaming device of claim **46**, wherein the symbols include at least one extender symbol which extends one or more symbols which occur on the cards across the cards.

56. The gaming device of claim **55**, wherein the extender symbol also functions as a wild symbol.

57. The gaming device of claim **46**, wherein the symbols include at least one extender symbol which extends one of the symbols which occurs on the cards across a predetermined number of cards.

58. The gaming device of claim **46**, wherein the symbols include at least one extender symbol which extends one of the symbols which occurs on the cards across a random number of cards.

59. The gaming device of claim **46**, wherein the symbols include at least one extender symbol which extends a plurality of the symbols which occurs on the cards across a predetermined number of cards.

60. The gaming device of claim **46**, wherein the symbols include at least one extender symbol which extends a plurality of the symbols which occurs on the cards across a random number of cards.

61. A method of operating a gaming device, said method comprising the steps of:

- (a) displaying a plurality of cards having a plurality of symbols, said symbols including at least two complimentary wild symbols;
- (b) randomly selecting and displaying certain of the cards to a player;
- (c) forming a resultant wild symbol when said two complimentary wild symbols occur on related cards; and
- (d) transforming at least one symbol which occurs on the cards to one of the plurality of symbols when the resultant wild symbol is formed by said sets of complimentary wild symbols.

62. The method of claim **61**, wherein the related cards are adjacent cards.

63. The method of claim **61**, wherein the related cards are non-adjacent cards.

64. The method of claim **61**, which includes a plurality of sets of complimentary wild symbols and which includes the step of forming a plurality of resultant wild symbols on the cards, wherein each resultant wild symbol is formed from one of said sets of complimentary wild symbols.

65. The method of claim **61**, which includes the step of providing an award to the player if the resultant wild symbol causes a winning combination of symbols on the cards.

66. The method of claim **61**, wherein the award is selected from the group consisting of: at least one credit, a multiple of a player's wager and at least one free play of the cards.

67. The method of claim **61**, which includes the step of providing an award to the player when the resultant wild symbol is formed on the cards.

68. The method of claim **61**, which includes the step of extending one of the symbols which occurs on the cards across a predetermined number of cards when at least one extender symbol occurs on the cards.

19

69. The method of claim **61**, which includes the step of extending one of the symbols which occurs on the cards across a random number of cards when at least one extender symbol occurs on the cards.

70. The gaming device of claim **61**, which includes the step of extending a plurality of the symbols which occur on the cards across a predetermined number of cards when at least one extender symbol occurs on the cards.

71. The gaming device of claim **61**, which includes the step of extending a plurality of the symbols which occur on the cards across a random number of cards when at least one extender symbol occurs on the cards.

72. The method of claim **61**, wherein the method is provided to a player through a data network.

73. The method of claim **72**, wherein data network is an internet.

74. A method of operating a gaming device, said method comprising the steps of:

20

(a) displaying a plurality of cards having a plurality of symbols, said symbols including at least two complimentary wild symbols;

(b) randomly selecting and displaying certain of the cards to a player;

(c) forming a resultant wild symbol when said two complimentary wild symbols occur on related cards; and

(d) causing the resultant wild symbol formed on the cards to function as an extra symbol on the cards.

75. The method of claim **74**, wherein the method is provided to a player through a data network.

76. The method of claim **75**, wherein the data network is an internet.
